UNITED STATES PATENT OFFICE.

JOHN D. SANDERS, OF LONE OAK, TEXAS.

OPEN LINK.

SPECIFICATION forming part of Letters Patent No. 235,457, dated December 14, 1880.

Application filed August 3, 1880. (Model.)

To all whom it may concern:

Be it known that I, JOHN DANIEL SANDERS, of Lone Oak, in the county of Hunt and State of Texas, have invented a new and useful Improvement in Open Links, of which the following is a specification.

Figure 1 is a perspective view of the improvement. Fig. 2 is a plan view of the improvement closed. Fig. 3 is an edge view.

10 The object of this invention is to furnish open links for connecting trace-chains to whiffletrees, and for various other purposes, so constructed that they can be readily applied and detached without the use of tools, will be fastened automatically when closed, and will not be liable to become accidentally detached.

15 Similar letters of reference indicate corresponding parts.

A represents the body or main part of the link, the ends of which do not meet, space being left for the insertion of a whiffletree-ring, a chain-link, or other object to which the link is to be attached. One end of the body A is slightly beveled, and is slotted longitudinally 20 to receive the tenon formed upon the end of the short bar B, which is hinged in place by a rivet or screw. The other end of the body A is beveled for the correspondingly-beveled end of the bar B to fit against. In the outer side 25 of the beveled end of the body A is formed a longitudinal shoulder, C, to receive the free end of the spring-latch D, which is secured by a rivet or screw at its other end in a recess, F,

formed in the outer side of the bar B. The free end of the spring-latch D projects a little, 35 so that it can be raised from the shoulder C with the fingers in opening the link.

Thus far the construction does not differ substantially from what is already known to the public; but my improvement consists in forming upon the outer side of the free end of the bar B a lip, E, to cover and protect the free end of the spring-latch D, to prevent anything from striking against the free end of the said spring-latch and opening the link accidentally 40 when the link is in use. The lip E also serves as a convenient handle in opening the link.

When the bar B is pressed down into place in closing the link, the spring-latch D springs into place and fastens the link automatically. 50

The solid side of the body A of the link is designed to be made heavier than the open side, to prevent the link from springing open when subjected to a heavy draft-strain.

Having thus fully described my invention, 55 I claim as new and desire to secure by Letters Patent—

In open links, the lip E, arranged on the outer side of bar B, to both cover the spring-latch and serve as a handle in opening the 60 link, as set forth.

JOHN DANIEL SANDERS.
